UNITED STATES PATENT OFFICE.

JAMES M. ROBERTS, OF FREDONIA, KENTUCKY.

HOLDER FOR MINERS' LAMPS.

1,271,368.

Specification of Letters Patent. Patented July 2, 1918.

Application filed October 13, 1917. Serial No. 196,433.

To all whom it may concern:

Be it known that I, JAMES M. ROBERTS, a citizen of the United States, residing at Fredonia, in the county of Caldwell and 5 State of Kentucky, have invented certain new and useful Improvements in Holders for Miners' Lamps; and I do hereby declare the following to be a full, clear, and exact description of the invention, such as 10 will enable others skilled in the art to which it appertains to make and use the same.

This invention relates to lamp holders and more particularly to lamp holding devices for miners' hats and the primary object of 15 this invention is to provide an improved type of lamp holder which can be readily attached or detached from the miner's hat and which is so formed as to take most of the weight of the lamp off of the visor of the 20 cap and distribute the same around the head of the wearer.

Another object of the invention is the provision of an improved lamp holding device for miners' hats which includes a plate 25 curved so as to conform to the curvature of a hat and an adjustable flexible band for extending around the head of the wearer to hold the device in position.

A further object of the invention is to 30 provide a lamp holding device for a miner's hat which is durable and efficient in use, one that is simple and easy to construct and one that can be placed upon the market at a reasonable price.

35 With these and other objects in view the invention consists in the novel construction, arrangement and formation of parts, as will be hereinafter more specifically described, claimed and illustrated in the accompanying 40 drawing, forming a part thereof, in which:

Figure 1 is a perspective view of a miner's cap showing the improved holder attached thereto.

Fig. 2 is a plan view of the improved 45 holder removed from the cap.

Fig. 3 is a front elevation of the improved lamp holder, and

Fig. 4 is a detail section taken on the line 4—4 of Fig. 2.

50 Referring to the drawing in detail, where- in similar reference numerals designate cor- responding parts throughout the several views, the numeral 1 generally indicates the improved lamp holding device, which is 55 adapted to be attached to the ordinary type of miner's cap 2.

The lamp holding device 1 includes the body plate 3, which is preferably formed of a single piece of sheet metal, which is curved transversely to conform to the curvature of 60 the cap 2. The body plate 3 consists of a centrally enlarged guard plate 4 and re-duced rearwardly extending curved arms 5, which are adapted to engage the sides of the crown 6 of the cap 2. The enlarged guard 65 plate 4 is bent outwardly and downwardly as at 7 to form a lamp receiving base. The lamp receiving base rests on the visor 8 of the cap 2 and is inclined downwardly to 70 conform to the inclination of the visor. An ear 9 is formed integral with the central upper portion of the guard plate and is bent forwardly and downwardly as at 10 in spaced parallel relation with the guard plate and a resilient spring clip 11 is positioned 75 between the ear 9 and the guard plate 4 and is secured in position therebetween by suit-able rivets or any fastening element 12. The free ends of the resilient spring clip 11 are flared outwardly as at 13 so as to facili- 80 tate the entrance of a miner's lamp there- between.

The free ends of the spring arms 5 of the body plate are each provided with an open- 85 ing 14 and a flexible strap 15 is looped through the same. One of the straps 15 is provided with an adjusting buckle 16 while the other has formed therein a plurality of openings 17 for co-operation with the buckle. 90

In operation of the improved lamp 95 holder the same is positioned on the hat and the flexible straps 15 are adjusted to the head of the wearer, these straps take a portion of the weight of the holder and lamp off of the visor 8 of the cap and distribute 100 the same around the head of the wearer. The lamp supporting base 7 engages the visor of the cap and forms a rest for the lamp. The miner's lamp which is shown in dotted lines in Fig. 1 may be of any pre-ferred type and is positioned between the arms of the resilient spring clips and on the base plate 7. By this arrangement the lamp is securely held in position and the weight of the same is distributed through- 105 out the entire area of the hat.

In practice, I have found that the form 110 of my invention, illustrated in the accom- panying drawings and referred to in the above description, as the preferred embodi- ments, is the most efficient and practical; yet realizing the conditions concurrent with

the adoption of my device will necessarily vary, I desire to emphasize the fact that various minor changes in details of construction, proportion and arrangement of parts 5 may be resorted to, when required, without sacrificing any of the advantages of my invention as set forth.

What I claim as new is:—

- 10 1. A lamp holder for miners' caps comprising a body plate including an outwardly bent lower portion for engaging a vizor of the cap, a central enlarged guard plate, and rearwardly extending reduced spring arms, a resilient clip secured to the central enlarged plate for detachably receiving a lamp, and adjustable straps carried by the terminals of said arms, as and for the purpose specified.
- 15

2. A lamp holder for miners' caps comprising a body plate formed of a single sheet 20 of sheet metal having the lower portion thereof reduced and bent outwardly, an ear formed on the upper edge of the plate and bent downwardly in spaced parallel relation to the body of the plate, a resilient clip positioned between the ear and the body of the plate, means extending through the ear to hold the clip in position, and means for securing the plate to a cap. 25

In testimony whereof I affix my signature 30 in presence of two witnesses.

JAMES M. ROBERTS.
